UNITED STATES PATENT OFFICE

ARTHUR G. STRAND, OF MINNEAPOLIS, MINNESOTA, ASSIGNOR TO SIMPLEX HEAT REGULATOR COMPANY, OF MINNEAPOLIS, MINNESOTA, A CORPORATION OF MINNESOTA

THERMOSTATIC INSTRUMENT

Application filed November 4, 1927. Serial No. 231,150.

This invention relates to a thermostatic instrument and more particularly to a thermostatically actuated means for making and breaking contacts in electrical circuits used to control devices for regulating heating elements to control the temperature in a room or space to be heated. In such instruments the engagement of the two or more contacts is controlled by a thermostatic member usually placed in the rooms to be heated. Said member moves slowly and with a rigid bar moved by the thermostat into engagement with fixed contacts, there is a very light engagement of the bar and contacts when they first come into engagement, and just before they come into engagement there is, of course, a very small space therebetween. This is apt to cause sparking or arcing which is objectionable. It is desirable to have a mechanism which is quite sensitive and will operate on a variation of a very few degrees of temperature.

It is an object of this invention, therefore, to provide a thermostatic instrument comprising a contact making and breaking means which will be quite sensitive and which will act with a quick make and break action.

It is another object of the invention to provide a thermostatic instrument comprising spaced contacts and having a thermostatically moved elongated strip of thin resilient material disposed between said contacts with its flat sides directed toward the same, said strip being slightly bowed and under tension so that it will snap from engagement with one contact into engagement with the other contact.

It is more specifically an object of the invention to provide a thermostatic instrument comprising an adjustable member having spaced contact points thereon and a thermostatically movable member comprising a comparatively narrow strip of thin resilient metal disposed between said contact points and in a plane substantially perpendicular to the axes of said points, said strip being slightly bowed and under tension, whereby it will snap from engagement with one point, into engagement with the other, to-

gether with means for adjustably holding one end of said strip.

These and other objects and advantages of the invention will be fully set forth in the following description made in connection with the accompanying drawings, in which like reference characters refer to similar parts throughout the several views and in which:

Fig. 1 is a view in front elevation of a thermostatic instrument embodying the present invention;

Fig. 2 is a vertical section taken on line 2-2 of Fig. 1 as indicated by the arrows;

Fig. 3 is a vertical section taken on line 3-3 of Fig. 2, as indicated by the arrows.

Referring to the drawings, a device is shown comprising a casing 5 adapted at its lower end to receive and hold a clock 6. Said casing has a flat plate forming its front, and said plate has at its top portion a projecting substantially U-shaped plate 5^a, the front portion of which is provided with a scale 7 comprising graduations adapted to indicate degrees of heat. While these graduations can be variously designated, in the embodiment of the invention illustrated they are shown as numbered from 60 to 80 indicating temperatures ranging from 60 to 80° Fahrenheit.

The front of the casing 5 which is in the form of a flat plate, has a post 8 secured adjacent one side thereof, to which is attached by a screw 8^a one end of a thermostat 9, said member 9 being formed of a flat strip comprising a plurality of metals, said strip being substantially semi-cylindrical in form and having a straight terminal arm 9^a. A bar 10 is attached to the end of the arm 9^a and extends downward in front of the casing 5.

The arm 10 has an inwardly projecting end 10^a having a slot therethrough into which projects a tongue 11^a formed on the end of an elongated comparatively narrow strip 11 of thin elastic metal, such as copper or phosphor bronze, the bar 10 being made of similar metal. The upper end of said strip 11 has a shank 11^b projecting through a slot in the lower side of the member 12, substantially U-shaped in form, having a por-

tion extending upward along bar 10 and riveted thereto by the spaced rivets 13, the member 12 having a portion 12^b bent around the front side of the arm 9^a. The member 5 is preferably also made of the same material as bar 10 which is quite thin and somewhat resilient, and the lower terminal arm thereof which receives the upper end of strip 11 may be bent upwardly or downwardly somewhat to place member 11 under more or less pressure. The member 11 has adjacent its central portion and secured thereto, small disks 11^c forming contact members. Said member 11 normally is slightly bowed so that it is under some tension. The member 5 has secured thereto by the screws 14 thin somewhat arcuate plates 15. A plate or block 16 illustrated as formed of insulating material, is provided, which block has a thimble 17 secured thereto, pivoted to the casing 5 about a pivot pin 18. The block 16 carries spaced posts 19 in which are threaded the contact screws 20 and 21 respectively, said screws being shown as having slotted heads and having reduced contact end portions 20^a and 21^a respectively. The posts 19 have reduced shanks extending through plate 16 and threaded to receive the clamping nuts 19^a. The plate 16 has secured to its under side or the side adjacent casing 5, a pointer 22, the upper end of which is bent to move over the front of plate 5^a and said pointer has a pointed end co-operating with the graduations 7. The plate 16 also has a small plate 23 having spaced upwardly extending arms 24 with which bar 10 is adapted to engage. Plate 16 also has resilient arms 25 secured thereto by the nuts holding posts 19 in place, which arms extend toward casing 5 and frictionally engage at their ends with the plates 15. It will be seen that the member 11 is disposed between the contact points 20^a and 21^a and is disposed in a plane substantially perpendicular to the surface of the plate 16 and substantially perpendicular to the common axis of screws 20 and 21.

In operation the device shown is placed in the room to be heated and the pointer 22 will be moved to have its point indicate on the scale 7 the temperature which it is desired to maintain in said room. When pointer 22 is moved, the block 16 swings about the axis of pivot 18 and the position of the contact members 20 and 21 is varied in relation to the strip 11 and thermostat 9. The strip 11 takes the position in engagement with either one of the contact points 20^a or 21^a. When the temperature changes and the thermostat 9 moves the bar 10, the member 11 will be swung at its bottom and will pass the central position in relation to bar 10 and the strip 11 at a certain point will snap out of engagement with contact 20^a as shown and into engagement with contact 21^a. When the strip 11 or its contacts 11^c engage one of the

contacts 20^a or 21^a, a circuit is usually closed, causing operation of a half-revolution motor or some other motor and after the same has operated as desired, the circuit is opened so that another control operation will not take place until the contact 11^c again engages the other one of the contacts 20^a or 21^a. When the temperature again changes sufficiently the thermostat 9 will again move the bar 10 and member 11 will be swung to the other side of its central position so that it will snap into engagement with the opposite contact. One of the contacts 11^c is thus always normally in contact with one of the points 20^a or 21^a and does not break such engagement until strip 11 is in position to break the engagement very quickly and also quickly move into engagement with the other contact. The strip 11 as stated is slightly bowed and under tension and this tension can be regulated by adjusting the lower terminal of the member 12. This can be raised or lowered to increase or decrease the tension on strip 11 so that it will have the desired action.

The stops 24 are provided both to keep the pointer 22 within the limits of scale 7 and to prevent a reverse action of the member 11. The stops 24 will engage the sides of bar 10 when the point of the pointer 22 is substantially at the ends of scale 7. Also, when the temperature has cooled to a certain point and strip 11 has been moved to bring one of its contacts 11^c into engagement with point 21^a, if unlimited movement of the bar 10 were permitted, strip 11 would eventually be bodily carried to the left as shown in Fig. 3 and brought into engagement with contact 20^a. This might happen when the temperature dropped quickly and the instrument would then be in the wrong position for the prevailing temperature. By having the stops 24 the bar 10 will engage the stop before this reverse action or bodily movement of the strip 11 takes place. The arms 25 have sufficient friction against the plates 15 to hold the block or plate 16 in the position to which it is moved. The bar 10 is made of the same material as the strip 11 so that there will be no differential action of these parts due to expansion or contraction in varying temperatures.

From the above description it is seen that applicant has provided a very simple and efficient thermostatic instrument. The switch involved acts very quickly in making and breaking the contact and at the same time is extremely sensitive. The device in practice will operate to move member 11 from one of the contact points to the other with a difference of two or three degrees in temperature. The device is simple in construction and quite positive in operation. The same has been amply demonstrated in actual practice and found to be very successful and efficient.

It will, of course, be understood that vari-

ous changes may be made in the form, details, arrangement and proportions of the parts, without departing from the scope of applicant's invention, which, generally stated, 5 consists in a device capable of carrying out the objects above set forth, in the novel parts and combinations of parts disclosed and defined in the appended claims.

What is claimed is:—

- 10 1. A device of the class described, having in combination, a plate mounted for swinging movement, a pair of spaced contact screws carried thereby, a pointer secured to said plate, a temperature scale with which said pointer co-operates, a thermostat, a member movable by said thermostat, a thin resilient strip carried by said member and disposed with its central portion between said contact screws and in a plane substantially normal 15 to the surface of said plate and the axes of said contact screws, said strip being slightly bowed and under tension, and stops on said plate limiting the relative movement of said plate and member.
- 20 2. A device for regulating a heat generator having in combination, a member having a supporting plate, a normally curved member secured at one end to said plate, said curved member being constructed and arranged to be moved to vary the curvatures thereof solely by changes in the temperature of the gaseous medium surrounding the same, a member secured to the other end of said curved member having spaced holding means,
- 25 35 a slightly bowed strip of resilient material carried at its ends by said means, a pair of contact members respectively disposed at opposite sides of said strip adjacent the center thereof, said contact members and strip being relatively movable whereby under the action of said curved member said strip will snap from one contact to another upon a certain variation in the temperature of said gaseous medium.
- 40 45 3. A device for regulating a heat generator having in combination, a casing, a temperature indicating scale carried on said casing, a pointer cooperating with said scale, a thermostatic member movable only by temperature changes of the atmosphere, said member being secured at one end to said casing, a member carried by the other end of said thermostatic member having spaced means thereon, a strip of slightly bowed resilient material extending between said means and carried thereby, a pair of contacts at either side of said strip adjacent the center thereof, said pointer being movable over said scale to indicate different temperatures, and to change the relationship of said contacts to said strip and thermostat whereby, by action of said thermostatic member, said strip will snap from one contact to another substantially at the temperature indicated by said pointer.

4. In a heat regulator, a support, a thermostatic element curved to at least a semi-circle, secured at one end to said support, said element terminating in a substantially radial arm, a slightly bowed strip of resilient material secured at least at one end to said arm, means for securing the other end of said strip, a pair of contact members disposed at opposite sides of the medial portion of said strip, said contacts and said strip being relatively movable whereby under the action of said curved thermostatic element said strip will snap from one contact to another upon a predetermined variation in the temperature of the gaseous medium to which said thermostatic element is subjected.

In testimony whereof I affix my signature.
ARTHUR G. STRAND.
